UNITED STATES PATENT OFFICE.

AXEL S. CARLSON, OF LOS ANGELES, CALIFORNIA.

WATER-HEATER.

1,216,942.

Specification of Letters Patent. Patented Feb. 20, 1917.

Application filed April 26, 1916. Serial No. 93,762.

To all whom it may concern:

Be it known that I, AXEL S. CARLSON, a citizen of the United States, residing at Los Angeles, in the county of Los Angeles and State of California, have invented new and useful Improvements in Water-Heaters, of which the following is a specification.

My invention relates to a water heater and pertains particularly to a combined water heater and stove burner.

It is an object of this invention to provide a water heating device which utilizes the heat which radiates from the burner of a gas or oil stove and the heat reflected from the bottom of a utensil disposed over the burner.

Another object is to provide a water circulating system which is adapted to be interposed between a fuel burner and grate bars of a stove and will permit the heating of water therein simultaneous with the heating of a utensil disposed upon said grate bars.

It is another object to provide means whereby a utensil disposed upon the grate bars of a stove having a gas or oil burner, will act to prevent the escape of the heated air and will cause it to be deflected in a downwardly direction.

Another object is to provide a device of the character described, with means whereby a circulation of air will be maintained throughout the device.

It is an object to provide the draft circulation means with adjustments for retarding the passage of the warm air from within the device.

It is another object to so arrange the heat coils within this device in a manner that will cause them to be heated by indirect heat and not be subjected to the flames of the burner.

Another object is to construct a cooking burner with means incorporated within its construction for heating a body of water by the utilization of the waste gases and further conducting the gases away from the burner to a vent pipe when necessary.

An object is to further utilize the heat by means of the use of a secondary grate member interposed over the conduit utilized to carry the heat to the vent pipe.

It is a further object to provide a combined cooking burner and water heater which will be simple in construction and

will utilize the maximum amount of heat developed by the burner.

Other objects will appear hereinafter.

The invention is illustrated in the accompanying drawings in which:

Fig. 1 is a view in plan of a gas or oil heat burner provided with my heat coil and a series of grate bars.

Fig. 2 is a sectional view as seen on the line 2-2 of Fig. 1 and discloses the detail construction of the preferred form of my invention.

Fig. 3 is a fragmentary view of the baffle plate mounting as seen on the line 3-3 of Fig. 2.

Fig. 4 is a plan view of a modified form of my device showing it provided with an auxiliary grate member and a heat conduit.

Fig. 5 is a view in vertical section as seen on the line 5-5 of Fig. 4 and discloses the detail construction of one of the modified forms of my device.

Fig. 6 is a horizontal section as seen on the line 6-6 of Fig. 5 and illustrates the relation which exists between the heat coil, the burner, and the central deflector.

Fig. 7 is a view in vertical section taken on a line similar to that of Fig. 5 and illustrates a second modified form of my device as provided with leg members independent of a stove.

Referring to the drawings, 10 indicates the top plate of a gas or oil burning stove formed with an opening 11 beneath which is disposed a suitable burner 12. The burner 12 is here shown as a gas burner and is positioned concentric to the opening 11 in the plate 10. The plate 10 is formed upon its upper face with a counter-bore 13 which is concentric with the opening 11 and of a larger diameter. This counter-bore is adapted to receive outwardly extending grate arms 14 and 15 which are formed integral with a cylindrical water coil housing member 16 which encompasses the upper portion of the burner 12. The grate members 15 are formed with inwardly projecting extensions which are radial with the housing member and extend from the inner wall of said member a suitable length to afford a support for the utensils disposed thereupon. The housing member 16 is formed at its upper marginal edge with an enlarged flare portion 17 which extends a distance above the

100

105

110

115

top of the grate members and is shown in Fig. 2 as providing a continuous support for a utensil 18. Mounted adjustably upon the lower edge of the housing member is a circular baffle plate 19 of larger outside diameter than the housing, and which has a series of ears 20 formed around its upper edge, said ears being formed with slots 21 throughout their length and adapted to be engaged by screws 22 which are positioned in the side walls of the housing. As seen in cross section, the baffle member is formed with an annular channel 23 which has an upturned inner wall 24. The wall 24 is circular and of an inside diameter slightly greater than the outer diameter of the burner 12. A draft space 25 occurs between the wall 24 and the burner 12 and thus insures that the burner will be supplied with sufficient oxygen to produce the proper combustion of the fuel.

The housing member 16 is of a larger diameter than the burner 12 and thus allows a water coil 26 to be arranged within said housing and around the burner. The ends of said coil communicate with a suitable water storage tank. The water coil may be of any preferred shape but I have here shown it as being arranged in three horizontally disposed strata, the two lower strata being composed of two convolutions of tubing, one disposed within the other and spaced a slight distance apart. The uppermost portion of the coil is formed in a helical shape and comprises sufficient tubing to completely fill the center of the coil unit. In this manner it is possible for a maximum amount of tubing to be placed between the grate bars and the heater and within a restricted diameter without subjecting any considerable length of tubing to the direct action of the burning fuel.

In the modified form of the invention illustrated in Figs. 4, 5 and 6 of the drawings, I have provided a slightly different water coil housing 27 which is shown as comprising a vertically disposed cylindrical member 28 and a horizontally disposed flange member 29 cast integral with said cylindrical portion. The flange 29 is formed with an internal bore 30 which is adapted to accommodate a series of concentrically disposed lid members 31 and 32. An outer housing member 33 preferably formed of sheet metal surrounds the cylindrical portion 28 of the inner housing member. The diameter of the outer member is considerably greater than the inner member and thus allows an annular space 34 to occur entirely around the inner member. A lower wall 35 is formed as a part of the member 33 and is provided with a central opening 36 which occurs adjacent and is spaced slightly from the burner 37. The space which occurs between the upturned

wall 38 of the opening 36 and the edge of the burner affords a constant supply of air to the burner.

In this form I have shown a burner having a central opening extending through it. As illustrated in Fig. 5 of the drawings, this central opening is provided with a draft regulating cone 39 which is adjustably mounted by means of a screw 40 upon a strap member 41 secured to the burner. Fig. 6 shows a plan view of the cone member 39 and illustrates it as having a series of corrugations 42 formed around its conical perimeter. The upper end of the member 39 is concaved and adapted to readily reflect the heat which falls thereupon.

It will be noted that when the inner housing member 28 is inclosed within the sheet metal inclosing housing 33 and a utensil is placed over the lids, the heat will be confined within and around the cylindrical portion of the inner housing member. In order to afford a circulation of heat through the heat coils and insure proper combustion of the fuel, I have provided a conduit 43 which leads the heat away to a vent pipe 44. In Fig. 4 an auxiliary grate member 45 is mounted over the conduit 43 at a convenient point and provides means for warming any desired utensil.

The second modified form of the invention as illustrated in Fig. 7 embodies the cast inner housing member of the former modification as well as the outer inclosing member, the difference being that this form is adapted to be used as a unit and not used in connection with a stove. A vent 46 is provided to connect with suitable piping to carry away the burnt gases. Leg members 47 are secured to the outer casing 33 and support it.

Attention is directed to the arrangement of the tubing in the heat coil 48 used in the modified form of the device. Owing to the fact that a burner having an open center is used in the modified form of the device, it is evident that the flame will rise from the burner in an annular body. This modified coil is provided with spaces within certain of its convolutions to allow the free passage of the flame to the utensil without being materially obstructed by the water coil. This arrangement acts to protect the water coil tubing from the injurious actions of a flame as it is impinged thereagainst.

In the operation of the preferred form of the invention, the housing member 16 with the baffle member 19 and the water coil 26 assembled therein are positioned within the opening 11 as shown in Fig. 2. When mounted in this manner the entire device will be suitably disposed in relation to the fuel burner which is supplied by means of a supply pipe 49. When the gas or other fuel is ignited within the burner, the flames

will rise and strike against the bottom of the utensil 18 which rests upon the annular flared portion 17 of the housing 16. It may be stated that the flare in the housing has been made to accommodate and provide an increased heating area to large utensils. The heat acting against the bottom of the utensil 18 will be reflected downwardly and through the spaces between the convolutions of the water coil tubing and will in this manner supply it with heat. After the heat has passed downwardly until it strikes the baffle plate 19 it will be drawn out from the housing through the annular opening 50 which occurs between the outer wall of the housing member 16 and the flared outer edge of the baffle member 19. In this manner a complete circulation of air will be maintained within the device and a maximum amount of heat will be absorbed by means of the manner in which the heat is reflected and used in heating the coil. It is evident that when the coil is once thoroughly heated it will assist in radiating heat to supply the utensil.

In the two modified forms of the device, the action of the burner and the heat radiation is identical. Air will rush in through the space 36 around the burner 37 and supply it with sufficient oxygen for combustion. A further supply of air is controlled by means of the cone member 39 which is mounted within the opening in the center of the burner. The flame in this burner will pass up through the space 51 between the water tubes and will come in contact with either the lid members 31 and 32 or a utensil resting thereupon. As in the preferred form of the device, the heat will be reflected in a downwardly direction and will pass under the lower edge of the cylindrical member 28 of the inner housing into a space 34. This space acts as a heat jacket and insures that the inner housing will be thoroughly heated throughout and will not be subjected to the chilling effects of the atmosphere. The conduit 43 leads from the inclosing member 33 and in Fig. 4 is shown as being provided to allow a portion of the remaining heat to warm a vessel resting upon the secondary grate 45. The remaining heat will be carried off through the vent pipe 44 to a chimney or other outlet.

It will thus be seen that I have provided a water heating system which may be conveniently used in connection with a gas or oil burner adapted to supply heat to cooking utensils without material alteration of the stove or without additional fuel expense.

I claim:

1. In a water heater, the combination with a burner, of a grate imposed over said burner, a removable plate adapted to rest upon said grate, a housing adapted to inclose said burner and extend beneath the

grate, a water circulating coil disposed within the housing and beneath the grate, means for maintaining a circulation of air throughout said housing, and means whereby the heating coil will be directly and indirectly heated by the burner. 70

2. In a water heater, the combination with a heater burner, of a water circulating coil disposed concentric with said burner, a grate member mounted over the water circulating coil, a housing inclosing said circulating coil, said housing being formed integral with said grate member, an annular rim formed around the upper marginal edge of said housing and adapted to terminate a distance above the grate member, a baffle plate adjustably secured beneath said housing and concentric with the burner, and means whereby the heat acting against the bottom surface of a utensil disposed upon said grate will be reflected and drawn downwardly between the convolutions of the water circulating coil. 85

3. A water heater, comprising a water circulating coil formed with a series of convolutions of tubing continuously arranged in superimposed strata, a heat burner mounted within the central opening of the lower convolution of said coil, a series of grate members disposed over said coil, a cylindrical housing extending downwardly from said grate members and partially inclosing said coil, a baffle plate adjustably mounted over the lower open end of the housing and having a central opening adapted to register with the heat burner, means for supplying the burner with sufficient air for combustion of the gas within the burner, and means whereby the heat thrown off from said burner will be reflected and drawn downwardly in the event that a utensil is disposed upon said grate members. 100

4. In a water heater, the combination with a stove having a top plate, a burner opening formed through said plate, a grate member adapted to be positioned over said opening, said member comprising a series of radially extending grate bars, a cylindrical housing member extending downwardly from said grate bars, an annular flared rim formed integral with the housing member and the grate bars and having its upper marginal edge terminating upon a plane above the grate bars, a helically wound water circulating coil disposed beneath said grate bars and within the housing, a heat burner disposed adjacent the lower end of said coil, the convolutions of the coil being so arranged as to lie substantially out of the path of travel of the flame from the burner, an adjustable baffle plate secured upon the housing and substantially inclosing the lower open end of said housing, a central opening within said plate adapted to register with the heat burner, 110 115 120 125 130

means for insuring a complete circulation of air through the water coil when the burner is in operation and a utensil is positioned upon the grate members, and means whereby the water coil will be directly and indirectly heated by the heat provided by the heat burner.

5. In a water heater, the combination with a burner, of a grate imposed thereover, 10 a water circulating coil interposed between said burner and grate, a coil housing secured around the coil and beneath the grate, and a baffle plate secured beneath the coil housing in a manner to cause the heat and flame 15 from the burner to circulate through the coil and out at the lower end of the housing.

6. In a water heater, the combination with a burner, of a water coil disposed there-around and thereabove, a housing inclosing 20 said coil, a grate formed over the upper

opened end of the housing, a utensil supporting ring formed around the upper edge of the housing whereby a utensil placed thereupon will substantially inclose the upper end of the housing, and a baffle plate 25 mounted over the lower end of the housing and positioned in relation thereto for the purpose of creating a down-draft through the housing.

7. In a water heater, the combination 30 with a burner, of a water coil thereover, a grate supported above the water coil, a cylindrical housing surrounding the water coil and supported by said grate, and an adjustable baffle plate secured over the lower end 35 of the housing and around the burner.

In testimony whereof I have signed my name to this specification.

AXEL S. CARLSON.
